(57) **CLAIM**

The ornamental design for a vacuum cleaner, as shown and described.

DESCRIPTION

FIG. 1 is a top right perspective view of a vacuum cleaner showing my new design.

FIG. 2 is a right view of a vacuum cleaner.

FIG. 3 is a left view of a vacuum cleaner.

FIG. 4 is a top side view of a vacuum cleaner.

FIG. 5 is a bottom side view of a vacuum cleaner.

FIG. 6 is a rear view of a vacuum cleaner.

FIG. 7 is a front view of a vacuum cleaner.

FIG. 8 is a bottom left perspective view of a vacuum cleaner.

FIG. 9 is an enlarged view of a vacuum cleaner taken from the circle part in FIG. 2.

FIG. 10 is an enlarged view of a vacuum cleaner taken from the circle part in FIG. 4; and,

FIG. 11 is an enlarged view of a vacuum cleaner taken from the circle part in FIG. 5.

The broken lines in the drawings depict portions of the vacuum cleaner that form no part of the claimed design.
